DESIGN FOR A DISPLAY CARD

Frederick A. Sunderhauf, Rutherford, N. J., assignor to Reynolds Metals Company, New York, N. Y., a corporation of Delaware

Application February 13, 1936, Serial No. 61,131

Term of patent 3½ years

To all whom it may concern:

Be it known that I, Frederick A. Sunderhauf, a citizen of the United States, residing at Rutherford, in the county of Bergen and State of New Jersey, have invented a new, original, and ornamental Design for a Display Card, of which the following is a specification, reference being had to the accompanying drawing, forming part thereof.

Fig. 1 is a perspective view of the display card showing my design; and

Fig. 2 is a front elevation thereof.

I claim:

The ornamental design for a display card, as shown.

FREDERICK A. SUNDERHAUF.
